(57) **CLAIM**

The ornamental design for a scale, as shown and described.

DESCRIPTION

FIG. 1 is a perspective view of a scale showing the new design;

FIG. 2 is a front elevational view thereof;

FIG. 3 is a right-side elevational view thereof, an elevational view of the left side being a mirror image;

FIG. 4 is a rear view thereof;

FIG. 5 is a top plan view thereof; and,

FIG. 6 is a bottom plan view thereof.

The portion shown in dashed lines forms no part of the claimed design.
